(57) **CLAIM**

The ornamental design for a carrying case for an optical launch fiber assembly, as shown and described.

DESCRIPTION

FIG. 1 is a perspective view of the carrying case in a closed condition, as viewed from the bottom of the case; FIG. 2 is a bottom plan view of the carrying case in a closed condition;

FIG. 3 is a top plan view of the carrying case in a closed condition;

FIG. 4 is a right side elevational view of the carrying case in a closed condition;

FIG. 5 is a left side elevational view of the carrying case in a closed condition;

FIG. 6 is a front elevational view of the carrying case in a closed condition;

FIG. 7 is a rear elevational view of the carrying case in a closed condition; and,

FIG. 8 is a top plan view of the carrying case in an open condition.

The structural features depicted in broken lines have been shown for purposes of illustrating portions of the carrying case that form no part of the claimed design.
